UNITED STATES PATENT OFFICE.

HENRY HIGGIN, OF NEWPORT, KENTUCKY, ASSIGNOR TO THE HIGGIN MANUFACTURING COMPANY, OF SAME PLACE.

DESIGN FOR A TOP-PROP NUT.

SPECIFICATION forming part of Design No. 32,659, dated May 15, 1900.

Application filed November 27, 1899. Serial No. 738,483. Term of patent 14 years.

To all whom it may concern:

Be it known that I, HENRY HIGGIN, a citizen of the United States, residing at Newport, in the county of Campbell and State of Kentucky, have invented a new and useful Design for Top-Prop Nuts, of which the following is a specification.

In the drawings, Figure 1 is a front view of a top-prop nut embodying my design, and Fig. 2 a plan view corresponding to Fig. 1.

The drawings show a top-prop nut with its

head provided with a plain central disk *a*, surrounded by a concentric band of radiating corrugations or flutes *b*, which are continued over the edges of the head.

I claim—

The design for a top-prop nut substantially as herein shown and described.

HENRY HIGGIN.
